CONTROL HEAD

Walter E. King, Houston, Tex., assignor to
 Reuben L. Waxler and Jess Hardcastle,
 Houston, Tex.

Application July 11, 1932, Serial No. 621,874

8 Claims. (Cl. 166—15)

The invention relates to an improvement in control heads of the general type used in connection with oil and gas wells wherein considerable pressure is encountered during the drilling and operation of the well.

It is one of the objects of the invention to provide an improvement in control heads wherein the tubing may be landed in the well and supported in the head in such a manner that the remainder of the control head may then be removed and the well completed with any desired type of fittings.

Another object of the invention is to provide a control head having a packing member upon which the tubing is adapted to be supported and wherein the remainder of the head exclusive of the packing member may be moved independently of the packing member.

Another object of the invention is to provide a control head having a detachable packing element upon which the tubing is adapted to be suspended.

Another object of the invention is to provide a drilling head through which the drilling operation may be performed, but which is provided with a sealing member which can be detached while in sealing position.

Other and further objects of the invention will be readily apparent when the following description is considered in connection with the accompanying drawings wherein

Fig. 1 is a central vertical section of a drilling or control head embodying the invention and showing the parts in sealing position.

Fig. 2 is a perspective view of one of the guide plates used in connection with the control head.

Fig. 3 is a central vertical section taken at right angles to the section of Fig. 1 and showing the end construction of the operating parts of the head.

Fig. 4 is an expanded view of the carrier and packing member used in connection with the invention and showing the manner in which they may be assembled and disassembled to leave the packing member in sealing position when the remainder of the head is removed.

The present invention is directed to somewhat the same subject matter as the patent to Reuben L. Waxler, No. 1,912,809 granted June 6, 1933, for an Improvement in blowout preventer.

It is usual construction in wells to have what is termed the surface casing, which is anchored firmly in the earth. This casing extends upwardly and is arranged to support the casing head, tubing head, and other fittings used in

connection with the well head assembly. In connection with the present invention, a casing head has been illustrated at 2. This head is shown as threaded at 3 to receive the casing, or it may be provided with a flanged construction for attachment in a well known manner. This body 2 is adapted to support the remaining fittings on the well and particularly a housing 5 for a blowout preventer, the novel features of which are about to be described. The housing 5 is shown as attached to the flange 6 by means of the bolts 7. A suitable packing ring 8 is provided to insure a seal about the body 2, and it should be particularly noted that the body 2 has an upstanding flange 10, which fits within the opening 11 in the body 5. In this manner the body 5 is centered and properly positioned with respect to the casing head 2, and when attached will be in proper position and rigidly fixed.

The body 2 is provided with a tapered seat or socket 14, which is usual construction with such casing heads and this tapered seat is adapted to receive a set of slips for supporting the tubing or drill stem or it may be used for receiving the packing elements 15, which are shown as being positioned in the bowl in Fig. 1. The elements 15, two of which are here illustrated, form a complete circle to seal about a pipe passing into the well and with the casing head. To accomplish this, the seal rings 16 and 17 are provided on the inside and outside respectively of each packing element. The two elements are seen in perspective view in Fig. 4 and in front elevation in Fig. 3.

The housing 5 is arranged to support operating mechanisms for positioning and withdrawing the packing elements 15 so that pipe and other pieces of equipment may be passed through the blowout preventer into the well and withdrawn from the well during the drilling or surfacing operations. With this in mind the body 5 is provided with a cap 20, which is attached thereto by the bolts 21 and which serves as a bearing for the operating spindle 22. This spindle 45 is anchored against longitudinal movement by bearing against the gland 23, which packs about the stem in the end 24 of the housing 5 and by a thrust bearing 26, which is positioned between the flange 27 on the spindle and the cap 20. In this manner the spindle 22 is mounted for rotation in the end of the housing and a packing ring 28 is provided to seal about the spindle in the end of the housing and a similar packing 29 is positioned in the cap 20. Thus 55

a complete seal is maintained about the spindle in the end of the housing.

This spindle 22 is threaded as at 30 and is passed into a yoke 31 so that rotation of the spindle causes horizontal sliding movement of the yoke 31 as viewed in Fig. 1.

The yoke 31 is shown in section in Fig. 3 and straddles the passage 32 through the housing 5 and the casing head 2. This yoke is provided with a slot such as 33 in each side thereof, which slot has a horizontal portion 34, best seen in Fig. 1 and an inclined portion 35 which is in turn joined to a second inclined portion 36. This slot 33 serves as a guideway to control the raising and lowering of the support or head 37, which carries the packing elements 15. This head 37 is provided on each side with an extending trunnion 38, which is of such size that it will fit within the slot 33. As seen in Figs. 1 and 3, the trunnions 38 are in their lowermost position, at which time the packing elements 15 are seated in the bowl 14. When, however, the spindle 22 is rotated and the yoke 31 moved to the right as viewed in Fig. 1, then the trunnions 38 will be caused to move in the slot 33 so that the head or support ring 37 will be raised vertically to withdraw the packing elements 15 from their seating or sealing position.

It seems obvious that the trunnions 38, however, must be held against lateral movement in order to prevent them from traveling with the yoke 31. To accomplish this, the guide plates 40 are provided and one of these is positioned on each side of the passage 32 and within the side portions 41 of the yoke 31. These side portions 41 are provided with grooves or trackways 42, which receive complementary formed edges 43 on the plates 40. The plates 40 are attached to a support ring 44 by means of the bolts 46, and this ring is in turn attached to the end 45 of the housing 5 by means of the bolts 47.

In this manner the plates 40 are rigidly secured in position and extend horizontally into the housing 5. The yoke 31 is slipped over the plates so that the edges 41 thereof will slide upon the portions 43 of the plate as a trackway. The plates 40 are each provided intermediate their ends with a vertical opening and guideway 50. This guideway is of sufficient width to receive the trunnions 38 and maintain them against lateral movement. Thus when the yoke 31 is moved to the right, as seen in Fig. 1, the trunnions 38 will be guided vertically by the guideways 50 and caused to move in the guideways 50 by the curvature or inclination of the slots 33. As seen in Fig. 3, the trunnions 38 pass through the plates 40 as well as the side members 41 of the yoke. The upper portion of the guideway 50 is preferably inclined as at 51 to assist in the assembly and removal of the parts.

The head 37 is provided with a central opening 53, which is of at least the same size as the passage 32 through the housing 5, and the casing head 2. The only movement of this head 37 is the vertical movement imparted to it by the trunnions 38. This head is, however, intended to support the sealing elements and is provided with a runway 54, which is in the form of an extending rib or shoulder on the lower part of the head. This shoulder is best seen in Fig. 3 and is arranged to receive the carriers 56, two of which are provided, and which are best seen in perspective in Fig. 4. These car-

riers serve as the connection between the sealing elements 15 and the head 37. They are arranged for vertical movement with the head 37 but are slideable laterally upon the head by means of the runways 54.

Each of the carriers 56 is provided with an overhanging shoulder 57 above the groove 58, which groove and shoulder together form the complementary portion on the carrier which meshes with the runway 54 on the head. Each of the carriers 56 is provided with a trunnion pin 60 on the outside edge thereof. These trunnion pins are arranged for movement in the guide slots 61, which are formed on the inside surface of the plates 40. These guideways comprise an inclined portion 62 and a substantially vertical portion 63, the vertical portion being provided to guide the carriers 56 vertically during the first part of their movement upwardly and the inclined portion 62 is arranged to cause upper and lateral movement of the carriers to withdraw the sealing members from the passage 32 so that tools and equipment of substantially the diameter of the passage 32 may be passed through the blowout preventer.

It should be remembered that the trunnions 38 cause vertical movement of the head so that the trunnion pins 60 will move upwardly in the vertical slot 63. When, however, the head 37 has moved to an elevation where the pins 60 are to pass from the vertical portion 63 and into the inclined slot 62, the carriers then begin a lateral or separating movement, one carrier moving to each side of the central passage. The vertical portion 63 of the slot maintains the packing elements 15 in proper alignment until they have been raised clear of the bowl 14. Whereupon, they are moved laterally in the housing 5 so that they will not interfere with any operations which are being carried on through the blowout preventer.

With the guideways 50 and 61 the positive control of the movement of the packing elements 15 is assured, so that they can not be misplaced by engagement with other parts of the blowout preventer or equipment passing through the well head. The size of each of these slots limits the movement of the parts and insures positive control at all times.

One of the principal features of the present invention is the construction of the parts so that the packing or sealing elements 15 may be positioned in the bowl 14 and the remainder of the blowout preventer removed. This includes the removal of the housing 5 and all of its associated parts, leaving only the packing elements 15 positioned in the bowl 14. Such a construction has been found to be desirable in landing tubing when the well is being brought in and in event of difficulties in connection with other portions of the well head or drilling equipment.

In order to permit the separation of the blowout preventer and its sealing members a special construction has been provided which is best seen in Fig. 4, wherein the carriers 56 are constructed with the cutout slots or recesses 70. These recesses extend transversely of the carriers 56 on the underside thereof and are arranged to receive the lugs or bosses 71, which are formed on the upper part of the sealing members 15. These lugs 71 are of such width that they fit within the recesses 70 when the parts are assembled as shown in Figs. 1 and 2. Fig. 4 shows the parts expanded to illustrate

the manner of their assembly. The carriers 56 are provided with the openings 73 through the body thereof and these openings extend through the carrier at an elevation such that 5 the passage is interrupted by the recesses 70.

The lugs 71 are provided with similar recesses 74 so that a through bolt, such as 75, may be passed through all of the passages when the lugs 71 are positioned in the recess 70. Fig. 1 10 shows the parts in this position, as does Fig. 3. The through bolt 75 serves to hold the packing elements to the carriers 56. The inner end of the passage 73 in the righthand side of Fig. 4 15 in the righthand carrier 56 is threaded as at 77 to receive the threaded end 78 of the through bolt 75. When the parts are assembled the through bolt is passed through the parts and rotated so that the part 78 screws into the threads 77. These threads are preferably a lefthand 20 thread. When the parts are assembled the blowout preventer is positioned on the well and is used in sealing about the pipe or tubing used in the well as desired. In event, however, it is necessary to remove the blowout preventer for 25 any reason whatever the present construction is adapted to be separated to leave the sealing elements in the casing head by removing the through bolts 75. Fig. 1 shows a socketwrench or tool 80, which is arranged to be passed 30 through an opening 81 in the end or cap 82 of the housing 5.

This socket wrench is arranged for connection to the end 83 of the through bolt 75. The thread in the socket wrench and on the bolt 35 will be opposite from that on the end 78, so that when the socket wrench is screwed up tightly on the bolt it will then begin to unscrew the end 78 from the threads 77 in the carrier 56. It is contemplated that in this manner the 40 throughbolts 75 can be removed from their position in the passages 73. The removal of these bolts removes the connection between the carriers 56 and the packing or sealing elements 15 so that they are entirely separate from each 45 other.

It is contemplated that at the time the blowout preventer is to be removed that the packing elements 15 will be held in position by a coupling on the string of pipe which is being positioned in the well. Fig. 3 shows in dotted lines 50 a string of pipe 85, which has a coupling 86 thereon. The lower shoulder 87 of this coupling rests upon the upper surface 88 of the packing elements 15. The weight of this string of pipe 86 holds the packing elements firmly in 55 position and when the through bolts 75 have been removed an elevator or hoist may be connected to the blowout preventer housing 5 and upon removal of the bolts 7, the entire blowout preventer may be removed from the well while 60 the same is sealed in between the packing elements 15. As soon as the blowout preventer has been removed a suitable tubing head or control head may be attached or the standard type Christmas tree fittings may be assembled and 65 placed in position.

In some instances it is desirable to replace the packing elements 15 without removing the blowout preventer from the well head and in 70 such cases the cap or end 82 of the housing may be removed and the spindle 22 rotated so that the trunnions 38 will be raised to their uppermost position. With the parts thus arranged the head 37 may be tilted from its normal position because of the inclined faces 51 on the slot 75

50. When the head 37 is in its highest position the lugs or trunnion pin 60 will be at the outer ends of the slots 61, so that tilting of the head 37 will cause the pin to move upwardly beyond the end 90. Thus if the carriers and packing 5 elements are to be removed the head will be raised and the lefthand side of the head, as viewed in Fig. 1, will be tilted downwardly so that the righthand side will move up and the pin 60 move beyond the tip 90 of the slot. With 10 the parts in this position the carriers 56 may be moved to the left by sliding them upon the runways 54, it being understood that the trunnion pin 60 on the left hand carrier 56 will, of course, slide out of the slot 61 on the left hand side, as seen in Fig. 1. The thickened portions 15 of the passage walls 50 in the guide plates 40 terminate as at 91 so that the trunnion pins may move along the plate as the carriers and packing elements are being withdrawn. When 20 the carriers have been withdrawn the through bolts 75 may be removed and the packing elements repaired or replaced and the parts inserted by reversing the operations described.

With the present construction it is contemplated 25 that the usual gate valve may be mounted above the body 2 in the assembly so that when the tubing is landed there will be a complete seal between the tubing and the casing. It is usual to either plug the tubing when the 30 same is being run in, or to provide a back pressure valve in the tubing. In either instance, it is usual to have the tubing closed so that with the present construction, when the casing is 35 closed around the tubing, the well is completely closed at the time the well is being brought in.

It is contemplated that when the present construction is used the gate valve will be positioned above the housing instead of below the housing, as is now the usual practice. Thus the 40 gate valve can be removed when the housing is removed and any desired fittings placed in position.

While one form of the invention has been 45 shown and described, it is to be distinctly understood that the same may assume various modifications, alterations and revisions without departing from the spirit of the invention as set forth in the appended claims, because the invention contemplates broadly a blowout preventer wherein the body or housing may be removed while the packing elements are in sealing 50 position.

Having described my invention, what I claim 55 is:

1. A blowout preventer to be mounted on a casing head including a housing, a pair of sealing elements therein to seal about a pipe and within the casing head, means to operate said elements from sealing to non-sealing position, 60 and means to detach said elements from said blowout preventer whereby a seal may be maintained by said elements about the pipe while said blowout preventer housing is removed.

2. In a blowout preventer, sealing means for 65 a pipe passing therethrough, operative means to actuate said sealing means, and detachable means connecting said sealing means to said operative means whereby the blowout preventer may be removed while said sealing means remains in operative position.

3. In a blowout preventer a pair of sealing members, a carrier for each member, means to move said carriers, and a detachable connection 70 between each carrier and its sealing member 75

- whereby the sealing member may remain in pipe sealing position and said blowout preventer be removed.
4. In a blowout preventer including a housing, 5 a pair of sealing members therein, a carrier for each member, means to move said carriers, and a detachable connection between each carrier and its sealing member whereby the sealing member may remain in pipe sealing position 10 and said blowout preventer be removed, said connection including a throughbolt.
5. A casing head bowl, a blowout preventer detachably mounted thereon, a sealing means detachably carried by said blowout preventer, 15 and means to detach said sealing means so that said blowout preventer may be detached from said sealing means when said sealing means is disposed in said bowl.
6. A drilling head of the character described 20 including a sealing element to close about a pipe in the well, a casing head support for said drilling head adapted to receive said sealing element,
- means in said drilling head to move said sealing element in and out of sealing position, and means whereby said drilling head may be removed independently of said sealing element.
7. A drilling head including a housing, a sealing element, means to move said element diagonally in said housing, a casing head to receive said sealing element and in which said element is adapted to be held by the weight of a string of pipe in the casing, and means in said 10 housing to release said element so that said drilling head may be removed while said sealing element is in said casing head.
8. A blowout preventer mounted on a casing head having a bowl, said preventer including a sealing portion, means to move said portion diagonally, and means whereby said preventer and said first means may be detached and removed from said sealing portion after said portion has been moved into said casing head bowl. 20

WALTER E. KING.
